UNITED STATES PATENT OFFICE

JUNIUS E. BUSEY, OF JACKSON, KENTUCKY, ASSIGNOR OF ONE-HALF TO MATT DEATON,
OF CHAVIES, KENTUCKY

MEANS TO PREVENT BATTERING OF NEW RAILS

Application filed November 12, 1929. Serial No. 406,673.

This invention relates to means adapted to be used while a railway is being equipped with new rails, which are higher than the old or worn rails, to prevent that end of a new rail 5 that is next to an old rail from being battered by the passage of a train from one of such rails to the other.

The invention has for a further object to provide means of the character stated which 10 shall embody a bridge plate adapted to be arranged upon the old rail and in contact with the end of the new rail so as to, in effect, arrange the treads of the adjacent end portions of the rails in a common plane, to the end that 15 a train may pass from one of the rails to the other without battering the end of the new rail.

The invention has for a further object to provide means of the character stated where- 20 in the bridge plate shall be provided with a horizontal tread portion adapted to align with the tread of the new rail, and with a sloping tread portion inclining from the horizontal tread portion to the tread of the old 25 rail so as to carry the wheels of the train from one of the tread portions to the other with the minimum of noise and jar.

The invention has for a further object to provide means of the character stated which 30 shall embody a member through the medium of which the bridge plate may be readily secured to one of the angle bars of the joint used to connect the new and old rails to permit the passage of the train during the laying of 35 the new rails.

The invention has for a further object to provide means of the character stated wherein the bridge plate attaching member shall be adapted to be secured to the intermediate 40 bolts of the joint and wherein the attaching member shall be adapted to permit the bridge plate to be adjusted vertically with respect to the joint, so as to permit the bridge plate to be used in connection with old or worn rails 45 of different heights.

The invention has for a further object to provide means of the character stated which shall embody a shim similar to the bridge plate and adapted to be secured thereon when 50 the horizontal portion of the bridge plate, due

to the wear in the rail, is located below the tread of the new rail, to the end that the old and new rails shall be provided with horizontally aligned end thread portions.

The invention has for a further object to 55 provide means of the character stated which shall be adapted to be used in connection with straight and curved rails, wherein the inner longitudinal edge of the bridge plate shall be adapted to be aligned with the gage sides of 60 straight rails on the mere application thereof to the rails, and wherein the bridge plate shall be provided with means through the medium of which its inner longitudinal edge may, after its application to the high rail of 65 a curve be brought into alignment with the gage side of the rail.

The invention is hereinafter more fully described and claimed, and illustrated in the accompanying drawings, wherein:—

Figure 1 is a top plan view illustrating the manner in which the invention is adapted to be applied to an old rail to prevent battering of the end of the new rail;

Figure 2 is a view in side elevation of the 75 part shown in Figure 1;

Figure 3 is a sectional view taken on the vertical plane indicated by the line 3—3 of Figure 2;

Figure 4 is a view partly in side elevation 80 and partly in vertical section illustrating the application of the tread shim to the bridge plate;

Figure 5 is a sectional view illustrating the manner in which shims may be employed in 85 connection with the attaching means for the bridge plate;

Figure 6 is a plan view of one of the shims, and

Figure 7 is a view in side elevation of a 90 slightly modified form of the bridge plate.

Referring in detail to the drawings, 1 designates an old rail and 2 a new rail of a railway being equipped with new rails, and 3 designates the inner and 4 the outer splice bar 95 of the joint by which the rails are connected. It is the practice, while a railway is being equipped with new rails, to connect the adjacent new and old rails so as to permit the passage of a train. As the new rail is higher 100

than the old rail, the train will, in passing from one of the rails to the other, batter down that end of the new rail that is connected to the old rail.

To prevent the battering of the end of the new rail, I have provided a bridge plate 5 which is arranged upon the tread of the old rail 1 with an end thereof in contact with that portion of the end of the new rail 2 that extends above the tread of the old rail. The bridge plate 5 is provided with a horizontal tread portion 6 which is arranged in alinement with the tread of the new rail 2, and it is provided with an inclined tread portion 7 which slopes downwardly from the horizontal tread portion to the tread of the old rail 1, the tread portions being equal in width to the treads of the rails. The bridge plate 5 is provided along its outer longitudinal edge with a depending flange 8 which contacts with the outer side of the head of the old rail 1.

The bridge plate 5 is adapted to be secured to the outer splice bar 4 by means which comprises a lower angle bar 9 and an upper angle bar 10. The angle bar 9 presents a horizontal flange 11 and a vertical flange 12. The flange 12 is secured to the splice bar 4 by the intermediate or central bolts 13 of the joint, and the flange 11 extends outwardly from the upper edge of the flange 12. The angle bar 10 presents a horizontal flange 14 which rests upon the horizontal flange 11 of the angle bar 9, and it presents a vertical flange 15 which extends upwardly from the inner edge of the flange 14 and is secured to the flange 8 by cap screws 16. The angle bars 9 and 10 are secured together by a bolt 17 which passes through a circular opening 18 in the flange 11 and a slot 19 in the flange 14.

The slot 19 extends transversely of the flange 14 so as to permit the bridge plate 5 to be adjusted transversely of the rails in order to aline the inner edge of the bridge plate with the gage sides of the heads of the rails. The flange 11 is greater in length than the flange 14, and is provided with two of the openings 18 so as to permit the bridge plate 5 to be arranged at either side of the transverse center of the joint, the position of the bridge plate depending upon which side of said center the old rail is located.

When two of the bridge plates are to be used, they will be made in rights and lefts, that is to say, one will be made for the old and new rails at one side of the track, as shown in Figures 1 to 5, and the other for the old and new rails at the other side of the track, as in Figure 7. Due to the increased length thereof, the lower angle bars for the bridge plates will not have to be made in rights and lefts, owing to the fact that the upper angle bars, that will be secured to both of the bridge plates, may be arranged upon

and secured to either end portion of the lower angle bars.

In securing the lower angle bar to the joint, the intermediate bolts 13 of the joint will be arranged with their heads outermost and in contact with the outer surface of the flange 12 of the angle bar.

When the bridge plate 5 is arranged upon the worn rail 1, the horizontal flange 14 of the angle bar 10 should rest fully upon the horizontal flange 11 of the angle bar 9. In the event, however, that the distance between the upper surface of the worn rail 1 and the horizontal flange 11 is such that the horizontal flange 14 will not contact with the horizontal flange 11, the angle bar 10 is supported from the angle bar 9 through the medium of a shim 20 which is arranged between the flanges 11 and 14 and is provided with a slot 21 for the reception of the bolt 17.

If the old rail is worn to such extent that the horizontal tread portion 6 of the bridge plate 5 occupies a plane below the tread of the new rail, a shim 22 is arranged upon the bridge plate so as to provide the bridge plate with a horizontal tread portion alined with the tread of the new rail. The shim 22 is similar in longitudinal section to the upper surfaces of the bridge plate 5, and its horizontal tread portion 23 overlies the horizontal tread portion 6 of the bridge plate, and its inclined tread portion 24 overlies the inclined tread portion 7 of the bridge plate.

The shim 22 is provided at the outer edge of its tread portion 23 with a depending flange 25 through the medium of which it is secured to the bridge plate 5. The flange 25 is provided with slots 26 which receive the cap screws 16, and it is clamped against the flange 15 of the angle bar 10 by the heads of the cap screws.

The bridge plate flange 8 is provided with a cap screw 27 near the inner or free edge of the head portion 7 of the bridge plate. This screw is used for the purpose of alining the inner edge of the bridge plate 5 with the gage side of the old high rail of a curve which, due to the wear thereof, has a narrow head. The cap screw 27 contacts with the outer side of the head of the rail and by turning it, the inner edge of the bridge plate 5 may be brought into alinement with the gage side of the head, the cap screw being secured in adjusted position by a jam nut 28.

It should be apparent from the foregoing description, taken in connection with the accompanying drawings, that the bridge plate 5 is adapted to carry the wheels of a train from an old rail to a new rail or from a new rail to an old rail in a manner to prevent the battering of the end of the new rail. It should also be understood that the angle bars 9 and 10 secure the bridge plate 5 to the outer splice bar 4 in a manner to hold the bridge plate firmly in position upon the old rail, and

that as they are located outwardly of the rails, they are not in the path of the wheels of the train.

It will be also understood that a firm connection between the angle bars 9 and 10 may be established, when the oil rail is of such height as to support the horizontal flange 14 of the angle bar 10 above the horizontal flange 11 of the angle bar 9, through the medium of the shim 20, that the thickness of the bridge plate may be increased, when the old rail is so worn as to position the horizontal tread surface 6 of the bridge plate below the new rail through the medium of the shim 22, that any desired number of shims of different thicknesses may be used in connection with the invention, and that the shims may be easily and quickly applied.

It should be still further understood that two of the bridge plates, one having its inclined tread portion extending to the left of its horizontal head portion and the other having its inclined tread portion extending to the right of its horizontal tread portion, will enable the new rails to be laid in four different directions, and that either of the bridge plates may be used in connection with the angle bars 9 and 10.

While I have described the principle of the invention, together with the structure which I now consider the preferred embodiment thereof, it is to be understood that the structure shown is merely illustrative and that such changes may be made, when desired, as fall within the scope of the invention as claimed.

I claim:—

1. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, and means adapted to secure the tread plate upon the old rail.

2. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, and means adapted to secure the tread plate to the rails.

3. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the

tread of the old rail, a member secured to the tread plate, a member adapted to be secured to the rails, and means connecting the members for relative vertical adjustment.

4. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, and vertically adjustable means adapted to secure the tread plate to the rails.

5. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, a downwardly extending flange at the outer edge of the tread plate and adapted to contact with the outer side of the head of the oil rail, and means adapted to secure the tread plate to the old rail.

6. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, a flange extending downwardly from the outer edge of the tread plate and adapted to contact with the outer side of the head of the end rail, a tread plate adjusting screw carried by the flange and adapted to contact with the outer side of the old rail, and means adapted to secure the tread plate to the rails.

7. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, a shim similar in longitudinal section to the upper surface of the tread plate and adapted to be arranged upon the tread plate to increase the thickness thereof, means securing the shim to the tread plate, and means adapted to secure the tread plate to the rails.

8. A device for preventing the battering of the end of a new rail joined to an old rail, comprising a bridge plate adapted to be arranged upon the old rail, the bridge plate having a horizontal tread portion adapted to

aline with the tread of the new rail and having a sloping tread portion adapted to extend from said horizontal tread portion to the tread of the old rail, a member secured to the tread plate and having a horizontal flange, a member adapted to be secured to the rails and having a horizontal flange underlying said first horizontal flange, and means connecting said flange to permit the tread plate to be adjusted transversely with respect to the rails.

9. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, a member secured to the tread plate and having a horizontal flange, a member adapted to be secured to the rails and having a horizontal flange underlying said first horizontal flange, a shim arranged between the flanges, and an attaching element passing through the flanges and shim.

10. A device for preventing the battering of the end of a new rail joined to an old rail, comprising a bridge plate adapted to be arranged upon the old rail, the bridge plate having a horizontal tread portion adapted to aline with the tread of the new rail and having a sloping tread portion adapted to extend from said horizontal tread portion to the tread of the old rail, a member secured to the tread plate and having a horizontal flange, a member adapted to be secured to the rails and having a horizontal flange underlying and longer than said first flange, said second horizontal flange being provided with relatively spaced openings, and an attaching element passing through said first horizontal flange and adapted to be engaged with one of the openings of said second horizontal flange.

45 11. In combination, new and old rails, splice bars bolted to the rails, a bridge plate adapted to be arranged upon the old rail, the bridge plate having a horizontal tread portion adapted to aline with the tread of the new rail and having a sloping tread portion adapted to incline from said horizontal tread portion to the tread of the old rail, a member secured to the outer side of the tread plate, a second member secured to the outer splice bar, and an attaching element engaging said members.

In testimony whereof I hereunto affix my signature.

JUNIUS E. BUSBY.
